THOMAS H. McCULLOCH, OF MONMOUTH, ILLINOIS, ASSIGNOR TO GEORGE H. RICH, OF GENEVA, ILLINOIS; AND GEORGE H. RICH ASSIGNOR TO THE HART GRAIN-SEPARATOR COMPANY.

Letters Patent No. 73,736, dated January 28, 1868.

IMPROVEMENT IN GRAIN-SEPARATORS.

The Schedule referred to in these Letters Patent and making part of the same.

TO ALL WHOM IT MAY CONCERN:

Be it known that I, THOMAS H. McCULLOCH, of Monmouth, in the county of Warren, and State of Illinois, have invented a new and useful Improvement in Grain-Separators; and I do hereby declare that the following is a full, clear, and exact description of the same, reference being had to the accompanying drawings, and the letters and figures marked thereon, which form part of this specification. In said drawings—

Figure 1 shows a side elevation of my invention,

Figure 2 is a vertical section of the same at the line *x* in fig. 3,

Figure 3 is a plan or top view thereof, and

Figure 4 is an isometrical view of one of the rollers in said machine.

Similar letters of reference in the different figures denote corresponding parts of my invention.

The nature of my invention consists in the employment of one or more cylinders whose convex surfaces are filled with cells or cups, of such dimensions as will allow grains of wheat to lie in the same, but not grains of oats, which are longer than grains of wheat, so that while wheat will lie securely in said cells, as hereinafter described, one end of the oats will project above the surface of the cylinder, and, as the cylinder revolves, the wheat is carried over, and deposited in its appropriate receptacle, while the oats are brushed back, and are carried out at their appropriate outlet, as hereinafter more fully described.

To enable those skilled in the art to understand the construction and operation of my invention, I will proceed to describe the same with particularity, making reference to the aforesaid drawings.

A represents the frame, supporting the box enclosing the mechanism for separating the grain, and B represents the hopper, through which the grain is introduced into the machine; A', in fig. 2, representing the lid or cover, which is removed in fig. 3. C D are two gear-wheels, fixed upon the ends of the shafts of the rollers G H, gearing into each other, as shown, which are also provided with drums for the belts *a b*, which pass around the drums E F upon the ends of the shafts of the revolving brushes L M. When motion is communicated to the wheel C by the handle *d*, or any other means, in the direction of the arrows marked upon the same, the wheels D E F, and the cylinders and brushes respectively thereunto attached, move as indicated by the arrows marked thereupon. The cylinders G and H are supported upon journals resting in suitable supports in the ends of the box enclosing them, the ends at which the hopper is placed being arranged higher than the opposite ends, and the two rollers or cylinders being arranged contiguous to each other, as shown, so as to form a gradually-inclined channel from the hopper H to the outlet N, where the oats pass out from the machine. The convex surfaces of said rollers are filled with the cells marked *c*, of the dimensions and for the purposes aforesaid. Directly above, and parallel to the said cylinders, are arranged the revolving brushes, marked L M in the drawings, operating as hereinafter described. Instead of brushes, as shown, any equivalent device may be employed.

Having described the construction of my invention, I will now describe its operation.

Motion being communicated to the mechanism in such a manner as to cause the two cylinders G H to revolve upwards, and in opposite directions, as indicated by the arrows aforesaid, and each brush L M in the direction of the cylinder directly below it, the grain is introduced into the machine through the hopper H, and, falling upon the revolving cylinders, the wheat is caught in the cells *c*, and carried over to the sides of the machine, falls upon the inclined bottom P, and passes into its proper receiver, as indicated by the red arrows in fig. 2. The oats in the mean time, on account of the dimensions of the cells *c* being insufficient to contain them, gradually pass along in the inclined channel between the cylinders, and go out at the spout N, as shown by the red arrows in fig. 3. Should any of the oats find a lodgment in the cells, still, on account of their length, one end would project above the surface of the cylinder, so that when it reaches the top, in its revolution, it is at once brushed back by the operation of the brushes, and thus the wheat is obtained perfectly clear and free from all larger grains, as oats and corn, and the-like.

Instead of two contiguous cylinders, as shown, a single cylinder may be employed; operating against a vertical partition, though, of course, the capacity of a single-cylinder machine would be only one-half of a

two-cylinder machine. The same principle may also be applied upon the interior surface of a hollow cylinder, by employing suitable conveyers and arrangements for that purpose.

Having described the construction and operation of my invention, I will now specify what I claim as new therein, and desire to secure by Letters Patent.

1. I claim the employment of one or more cylinders, with cellular convex surfaces, arranged and operating substantially as and for the purposes specified.

2. I claim, in combination with said cylinders, the employment of a brush or brushes, arranged and operating as and for the purposes specified and shown.

T. H. McCULLOCH.
